UNITED STATES PATENT OFFICE.

JOHN W. PAGE, OF COMO, MISSISSIPPI.

COTTON-SCRAPER ATTACHMENT FOR TURNING-PLOWS.

SPECIFICATION forming part of Letters Patent No. 660,800, dated October 30, 1900.

Application filed August 18, 1900. Serial No. 27,327. (No model.)

To all whom it may concern:

Be it known that I, JOHN W. PAGE, a citizen of the United States, residing at Como, in the county of Panola and State of Mississippi, have invented a new and useful Cotton-Scraper Attachment for Turning-Plows, of which the following is a specification.

My invention is an improved cotton-scraper attachment for turning-plows, one object of 10 my invention being to provide a simple cotton-scrapping attachment which is adapted to be applied to and used in connection with any make of plow having a detachable point.

A further object of my invention is to effect 15 improvements in the means whereby the cotton-scraper attachment is secured to the plow.

My invention consists in the peculiar construction and combination of devices herein-after fully set forth, and pointed out in the 20 claims.

In the drawings, Figure 1 is a perspective view of a plow provided with my improved cotton-scraper attachment. Fig. 2 is a detail perspective view of the moldboard of the plow 25 with the point removed. Fig. 3 is a detail perspective view of the reverse side of my improved cotton-scraper attachment. Fig. 4 is a landside elevation of a plow provided with my improved cotton-scraper attachment.

The plow, which is a turning-plow of the 30 usual type, has the moldboard A provided at its foot or lower edge with the usual ledge B, which projects forward therefrom, and the shoulder C at the rear side of said ledge adapted to form a seat for the usual detachable point, which is removed, as here shown, when 35 my cotton-scraper attachment is applied to the plow.

The cotton-scraper attachment 1 is of suitable 40 size and is approximately square in shape. The same may be formed either of plate or cast metal and is curved and adapted to fit on the face of the moldboard. The said cotton-scraper attachment 1 is provided near 45 one of its lower corners, corresponding with the landside of the plow, with an opening 2, which is adapted to register with the usual bolt-hole 3 in the foot of the plow. A plate 4 is adapted to be placed on the ledge B and 50 to fill the same flush with the face of the moldboard, the said plate being interposed between the ledge of the moldboard and the

inner side of the scraper attachment 1. The said plate has an opening 5, which registers with the openings 2 3, and a bolt 6 in said 55 openings serves to secure the foot of the scraper attachment to the foot of the plow, as will be understood. The plate 4 may be either formed with the scraper attachment or independently thereof. In order to prevent 60 the scraper attachment from turning on the bolt 6, I provide the same at its upper corner on its landside edge with a downturned lug 7, which bears against the landside edge of the moldboard A and of the plow-standard. 65 Where the scraper is made of plate-metal, the said lug 7 is formed by first cutting the plate on the line 8 to form the inner side of the lug, the latter being bent at right angles to the inner side of the scraper attachment, thereby 70 leaving a notch 9 in the inner upper corner of the latter.

It will be understood that my improved cotton-scraper attachment may be very readily applied to or taken from the common turning- 75 plow and that by its use dealers will be required to keep only the one variety in stock in order to supply the wants of their customers.

Having thus described my invention, I 80 claim—

1. A cotton-scraper attachment having a bolt-hole near its inner lower corner, for the purpose set forth, and a rearward-extending lug near its upper inner corner adapted to engage the landside edges of the standard 85 and moldboard of a plow, substantially as described.

2. In combination with a turning-plow having a moldboard, a cotton-scraper attachment curved to fit on the face of the moldboard 90 and having a rearward-extending lug near its inner upper corner engaging the landside edges of the moldboard and standard, and a bolt to secure the lower portion of said cotton-scraper attachment to the foot of the plow, 95 substantially as described.

In testimony that I claim the foregoing as my own I have hereto affixed my signature in the presence of two witnesses.

JOHN W. PAGE.
